(57) **CLAIM**
The ornamental design for an electric toothbrush handle, as shown and described.

DESCRIPTION

FIG. 1 is a front perspective view of an electric toothbrush handle showing our new design;
FIG. 2 is a right side perspective view thereof;
FIG. 3 is a rear perspective view thereof;
FIG. 4 is a bottom perspective view thereof;
FIG. 5 is a front elevational view thereof;
FIG. 6 is a rear elevational view thereof;
FIG. 7 is an enlarged top plan view thereof;
FIG. 8 is an enlarged bottom plan view thereof;
FIG. 9 is a right side elevational view thereof;
FIG. 10 is a left side elevational view thereof;
FIG. 11 is an enlarged, partial view of the electric toothbrush handle as shown in FIG. 1;
FIG. 12 is an enlarged, partial view of the electric toothbrush handle as shown in FIG. 2;
FIG. 13 is an enlarged, partial view of the electric toothbrush handle as shown in FIG. 3;
FIG. 14 is an enlarged, partial view of the electric toothbrush handle as shown in FIG. 4;
FIG. 15 is an enlarged, partial view of the electric toothbrush handle as shown in FIG. 5;
FIG. 16 is an enlarged, partial view of the electric toothbrush handle as shown in FIG. 6;
FIG. 17 is an enlarged, partial view of the electric toothbrush handle as shown in FIG. 9; and,
FIG. 18 is an enlarged, partial view of the electric toothbrush handle as shown in FIG. 10.

The broken lines shown in the drawings are for illustrative purposes only and form no part of the claimed design. The white areas within the broken lines form no part of the claimed design. In each of FIGS. 11-18, the solid wavy black line at the bottom of the respective figure represents an unclaimed boundary and forms no part of the claimed design.
